UNITED STATES PATENT OFFICE.

JOHN J. WINN, OF KIMBALL, SOUTH DAKOTA.

RAIL-FASTENING DEVICE.

1,142,742.

Specification of Letters Patent. Patented June 8, 1915.

Application filed December 17, 1913. Serial No. 807,304.

To all whom it may concern:

Be it known that I, JOHN J. WINN, citizen of the United States, residing at Kimball, in the county of Brule and State of South Dakota, have invented certain new and useful Improvements in Rail-Fastening Devices, of which the following is a specification.

This invention relates to an improved rail fastening device, and the principal object of the invention is to provide novel and useful means for effectually securing a rail to the cross tie, the latter being so constructed as to coact with the fastening device to rigidly 15 secure the rail upon the tie without the use of the customary spikes.

The invention still further contemplates the provision of means including a plurality of specially devised clamping plates so positioned with respect to the cross tie and the railway rail as to firmly engage the latter and bind against the former to rigidly and positively fasten the said rails against spreading or creeping during the passage of 25 rolling stock thereover.

The invention still further aims to provide a cross tie of such novel and peculiar construction as to provide an increased bearing surface for the rails and to coact with the fastening device in such a manner as to 30 lock the same against lateral or longitudinal movement independent thereof.

The above and additional objects are accomplished by such means as are illustrated 35 in their preferred embodiment in the accompanying drawings, described in the following specification and then more particularly pointed out in the claims which are appended hereto and form a part of this 40 application.

In describing my invention in detail reference will be had to the accompanying drawings wherein like characters denote like or corresponding parts throughout the several views, and in which:—

Figure 1 is a top plan view illustrating the application of the invention; Fig. 2 is a side elevation of the device as illustrated in Fig. 1; Fig. 3 is an end view of the improved railway tie with the railway rails and fastening device associated therewith; and Fig. 4 is a detail perspective view of one of the locking plates employed in connection with the present invention.

While interlocking rails, designated 1, have been illustrated in the drawings, the

fastening device and rail tie may be employed in connection with rails of ordinary construction.

Proceeding now with a description of the invention, 2 designates, as an entirety, my improved cross tie, the same being constructed of a single sheet of metal bent to provide a comparatively broad rail engaging surface 3. Along the longitudinal edges 65 of the rail engaging surface 3, the plate metal of which the tie is composed, is bent to extend downwardly at an acute angle to the said surface 3 as is illustrated to advantage in Fig. 3 of the drawings, the angular portion being designated 4. About midway 70 the depth of the depending portion of the metallic plate member, the sides of the rail tie, formed by the said depending portion extend substantially parallel as at 5 to a 75 convenient point where they are again bent to provide the base portion 6 of the rail, the latter, by reason of the angular or converged portion 4 of the tie bottom is somewhat narrower than the rail engaging or top 80 surface of the tie. To centrally brace the tie 2, the plate member, adjacent each longitudinal edge, is bent upwardly as at 7, the upwardly bent portions being contiguous and secured in any suitable manner, preferably 85 as indicated at 8. One of the upwardly extending brace portions 7 terminates in a longitudinally extending flange 9 disposed to overlap the other of the said brace portions and to engage the under surface of the top 90 portion 3 of the tie to which it is secured in any suitable manner, the said flange forming a reinforcing means for the rail engaging surface of the tie. By the tie formation above recited, it is apparent that a comparatively broad reinforced hollow metallic tie 95 has been provided, the original cost of which is reduced to a minimum without in any way affecting the efficiency of the device.

The rail engaging surface, as well as the converging sides or edges of the tie are serrated or gnarled to render more positive the locking of the fastening device thereupon. The said fastening device, in its preferred embodiment, comprises a plurality of metallic locking plates, arranged in pairs, one pair upon each side of the rail 1 to be fastened. One of the plates of each pair, designated as an entirety by the numeral 10 105 is composed of a substantially rectangular flat metal plate, the longitudinal edges of

which are bent at right angles to provide upstanding flanges 11, the inner of which is notched as at 12 for a purpose to be herein-after fully described. The inner end of 5 each locking plate 10 has formed integrally therewith a rail engaging locking tongue 13 disposed to overlap the base of the rail 1 to serve as a substitute for the now commonly used rail spikes. The other of the 10 flanges 11 is provided with openings (not shown) through which securing bolts 14 extend, the same being disposed, preferably, one adjacent each end of the said plates 10. The locking plates 10 are disposed, one upon each side of the rail 1, preferably, at diagonally opposite points. The other locking plates of each pair, designated as an entirety by the numeral 15, are likewise positioned at diagonally opposite 15 points, as illustrated to advantage in Fig. 1 of the drawings, the said plates 15 being provided with flanges 16 and a locking tongue 17 of the same construction as the flanges 11 and tongue 13 above mentioned. 20 Each flange of the plate 15 however, is notched as at 18 to form, with the notches 12, a seat within which the locking bolts 14 are fitted, the said bolts extending transversely of each pair of plates and terminating 25 in an angled extension 19 disposed to overlap the edge of the plate 15 to force the depending portion 20 formed integrally with the said plates 15 firmly against the serrated or gnarled surface of the diverged 30 portion 4 of the tie 5. The plate members 10 are also provided with depending portions 21, likewise disposed for engagement with the opposite gnarled side or edge of the tie 1 from that engaged by the coacting plate 15 in connection with which they 35 are used.

If desired, a washer 22, may be arranged over each locking bolt 14 to assist in forcing the extension 21 against the gnarled 40 surface of the tie, the said washers being maintained against the said extensions through the medium of nuts 23 threaded upon the bolt 14 to provide for the locking of the several plates incapable of lateral 45 or longitudinal movement independent of the tie. Preferably, the rail engaging surface of the tie is gnarled or serrated, as are also the inner or engaging surfaces of the extensions 20 and 21 and the under or 50 engaging surfaces of the several plates.

As a locking means for the nuts 23, a notched plate 24 is provided for each pair of locking members, the nuts being disposed to fit the notches, the latter (the plates 60 24 being held immovable) preventing rotation of the nuts. A bolt 25 is provided to maintain each plate 24 in proper place, the bolt extending through the flanges 11 of the locking plate 10 and having formed integrally adjacent one end, an annular flange

26 against which one end of an expansion helical spring 27 abuts, the opposite end of the said spring abutting the outer flange 11, the bolt 25, over which the spring is arranged, preventing a buckling of the latter when in use. The provision of the spring 27 will at all times maintain the plates 24 in proper place yet permit, by compressing the said spring, an adjustment of the nuts 23. 70

From the above, taken in connection with 75 the accompanying drawings, it is apparent that the rails 1 are locked against creeping or spreading upon the tie by reason of the several locking plates adapted for engagement therewith; that adjustment of the several locking plates may be effected by loosening the nuts 23 sufficiently to provide for the removal of the bolt 14 from the notches 18; and that by the peculiar tie formation, vertical movement of the fastening device 80 is rendered impossible, the same having first been tightened upon the tie in a manner necessary to the operation of the invention. 85

In reduction to practice, I have found that 90 the form of my invention, illustrated in the drawings and referred to in the above description, as the preferred embodiment, is the most efficient and practical; yet realizing that the conditions concurrent with the 95 adoption of my device will necessarily vary, I desire to emphasize the fact that various minor changes in details of construction, proportion and arrangement of parts may be resorted to, when required, without sacrificing any of the advantages of my invention, as defined in the appended claims. 100

Having thus fully described my invention, what I claim as new and desire to secure by Letters Patent, is:—

1. In a rail fastening device, the combination with the cross tie, of locking plates arranged upon each side of the rail, each plate being notched, the notches in the plates on each side of the rail being alined, lock means 110 maintaining the plates immovable relatively to the tie, said lock means fitting the notches aforesaid, and means forming a part of the several plates and engaging the base flange of the rail to serve as a fastening means. 115

2. In a rail fastening device, the combination with a cross tie, of a plurality of locking plates arranged upon the tie, said plates being disposed in pairs, one pair of plates upon each side of the rail, the plates of the respective pairs being notched, the notches of the several plates being alined, lock means maintaining each plate immovable relatively to the tie, said lock means fitting the notches aforesaid, and means forming a part of the several plates and engaging the base flange of the rail, as and for the purpose set forth. 120

3. In a rail fastening device, the combination with a cross tie, of a plurality of adjustable locking plates arranged in pairs 125

upon said tie, one pair of said plates being disposed upon each side of the rail, means formed integrally with each plate adapted for engagement with the said rail, and 5 means including a plurality of locking bolts extending transversely of each pair of plates for locking the same in adjusted position upon the tie, as and for the purpose set forth.

10 4. In a rail fastening device, the combination with a cross tie, a plurality of longitudinally adjustable locking plates arranged upon the said tie, the said plates being disposed in pairs, one pair upon each side of 15 the rail, locking tongues formed integrally with each plate, said tongues being disposed to overlap the base of the rail, an extension formed integrally with each plate, said extensions adapted to depend upon the sides 20 of the tie, and means including a plurality of locking bolts extending transversely of each pair of locking plates to maintain the said plates in adjusted position and the said plate extensions in engagement with the 25 sides of the tie, as and for the purpose set forth.

5. In a rail fastening device, the combination with a cross tie, of a plurality of locking plates adjustable longitudinally upon 30 the said tie, the said plates being arranged in pairs, one pair being disposed upon each side of the rail, a locking tongue formed integrally with each locking plate, said tongues being disposed to overlap the base

of the rail to fasten the same immovable 35 with respect to the tie, extensions formed integrally with each locking plate, the said extensions being disposed to depend upon the sides of the tie, flanges formed integrally with each locking plate, certain of the said 40 flanges having notches formed therein, and a plurality of locking bolts, the said bolts being disposed to extend transversely of each pair of locking plates, and to fit the said notches to lock the said plates immovable with respect to the tie. 45

6. In a rail fastening device, the combination with a cross tie, of a plurality of locking plates, said plates being arranged in pairs, one pair upon each side of the rail, 50 means carried by the said plates adapted for engagement with the rail, bolts extending transversely of each pair of locking plates, extensions formed integrally with the said plates, the said extensions being disposed to 55 engage the sides of the tie, an extension formed upon one end of each locking bolt, said bolt extensions being adapted for engagement with certain of the said plate extensions to lock the said plate in adjusted 60 position against the sides of the tie, as and for the purpose set forth.

In testimony whereof I affix my signature in presence of two witnesses.

JOHN J. WINN.
